FOREIGN PATENT DOCUMENTS

WO 2016054430 4/2016

Primary Examiner — Susan Moon Lee

(57) **CLAIM**

I claim the ornamental design for a portable hopscotch game, as shown and described.

DESCRIPTION

FIG. 1 is a front view of the portable hopscotch game.

FIG. 2 is a rear view thereof.

FIG. 3 is a left side view thereof.

FIG. 4 is a right side view thereof.

FIG. 5 is a top view thereof.

FIG. 6 is a bottom view thereof; and,

FIG. 7 is a perspective view thereof.
